CLAIM

The ornamental design for an exercise glove, as shown and described.

DESCRIPTION

FIG. 1 is a side view of an exercise glove showing my new design as it would appear mounted for use on a user's hand; FIG. 2 is a top plan view showing my new design in the unfolded configuration;

FIG. 3 is a bottom plan view showing my new design in the unfolded configuration;

FIG. 4 is proximal side view showing my new design in the unfolded configuration;

FIG. 5 is a distal side view showing my new design in the unfolded configuration;

FIG. 6 is a right side view showing my new design in the unfolded configuration; and,

FIG. 7 is a left side view of my new design in the unfolded configuration.
